(57) **CLAIM**

The ornamental design for a fire pit, as shown and described.

DESCRIPTION

FIG. 1 is an upper perspective view of a fire pit showing my new design.

FIG. 2 is another upper perspective of the fire pit taken along line 2-2 of FIG. 4.

FIG. 3 is a lower perspective view thereof.

FIG. 4 is a front elevation view thereof.

FIG. 5 is a left side elevation view thereof.

FIG. 6 is a right side elevation view thereof.

FIG. 7 is a rear elevation view thereof.

FIG. 8 is a top plan view thereof.

FIG. 9 is a top plan view taken along line 9-9 of FIG. 4; and, FIG. 10 is a bottom plan view thereof.

The broken lines shown in the drawings are for purposes of illustrating portions of the article that form no part of the claimed design.
